Primary Examiner — Kevin Rudzinski*Assistant Examiner* — Sean D Lough(74) *Attorney, Agent, or Firm* — Price Heneveld(57) **CLAIM**

The ornamental design for a gas burner, as shown and described.

DESCRIPTION

FIG. 1 is a front perspective view of a gas burner according to our design;

FIG. 2 is a front elevational view thereof, back, left, and

right views of the gas burner being identical thereto;

FIG. 3 is a top plan view thereof; and,

FIG. 4 is a bottom plan view thereof.

The broken line showings of various features are for the purpose of illustrating portions of the gas burner and form no part of the claimed design.
